Patented June 22, 1915.

UNITED STATES PATENT OFFICE.

HENRY L. COATS, OF MOSCOW, IDAHO.

GATE.

1,143,750.

Specification of Letters Patent. Patented June 22, 1915.

Application filed April 8, 1914. Serial No. 830,452.

To all whom it may concern:

Be it known that I, HENRY L. COATS, citizen of the United States, residing at Moscow, in the county of Latah and State 5 of Idaho, have invented certain new and useful Improvements in Gates, of which the following is a specification.

This invention relates to improvements in gate operating devices, more particularly to 10 the class of large farm and similar gates which are operative from a distance by a person from a vehicle or from horseback without alighting, and has for one of its objects to improve the construction and in- 15 crease the efficiency and utility of devices of this character.

Another object of the invention is to provide a simply constructed device which is partly automatic both in opening and clos- 20 ing.

With these and other objects in view the invention consists in certain novel features of construction as hereinafter shown and described and then specifically pointed out 25 in the claim; and in the drawings illustrative of the preferred embodiment of the invention—Figure 1 is a side elevation of the improved apparatus. Fig. 2 is an end elevation of the improved apparatus. Figs. 3 30 and 4 are enlarged details of the traveler devices.

Corresponding and like parts are referred to in the following description and indicated in all the views of the drawings by 35 the same reference characters.

The supporting frame comprises posts 10—11 erected at opposite sides of the gateway opening and provided with a connecting head member 12, the posts 10—11 being 40 high enough to permit the head member to be located a sufficient distance from the ground to enable teams to pass beneath it without interference. The posts 10—11 may be disposed at any distance apart and 45 the head member 12 disposed at any height according to circumstances without departing from the principle of the invention. A third post 13 is located at one side of the post 11 and connected to the latter by a head member 14. The post 13 and the head 50 14 correspond in height substantially to the gate, the head member 14 being preferably halved into the post 11, as shown at 15. The

three posts and the two head members are thus firmly united and supported in position. 55

The head member 12 is provided with a track represented as a whole at 16, while the head member 14 is provided with a similar track represented conventionally at 17. The 60 tracks 16—17 are formed inclined in opposite directions from the center or bowed upwardly, as shown.

The gate may be of any of the ordinary forms but should include vertical members 65 18—19 and an intermediate vertical member 20, and a conventional gate is shown which includes these features and likewise with horizontal bars 21 and braces 22. While a gate of this character is shown for illustration, 70 it will be understood that it is not desired to limit the invention to any specific form of gate as the improved device is applicable to any of the various forms of gates by making slight and unimportant 75 modifications in the construction. If a gate having wire members is employed the frame should include an intermediate vertical member to receive the flexible operating member, as hereinafter explained. The 80 terminal member 19 is extended upwardly as represented at 23 and is provided with a suspension bracket 24 carrying a roller 25 which engages upon the track 16. The member 24—25 thus forms a traveler upon 85 the track and thereby carries the outer end of the gate. The hanger 24 may be of any suitable construction, but will preferably be so constructed that it will not run off from the track, or what is commonly known as the 90 “can’t-come-off” kind. A similar hanger, indicated at 26, is connected to the member 18 and carries a roller 27 which operates upon the track 17 in the same manner as the hanger 24 and its wheel 25 operates in connection with the track 16. 95

The tracks 16—17 are precisely alike, or with their inclines of the same degree, so that when the gate 21 with its attachments is moved, for instance from closed into open 100 position, transversely of the gateway opening, the rollers running upon the adjacent inclined portions of the track will elevate the gate until the rollers arrive at about the center of the tracks, and then as the gate 105 continues into its open position the rollers

will travel down the second inclined portion of the track and depress the gate. By this means to open the gate it is only necessary to move the gate about one-half of its distance when the gate will be automatically moved for the remainder of the distance into open position by gravity as will be obvious. In closing the gate the same action takes place in reverse order. Thus, it is only necessary to move the gate either into closed or open position about one-half of the distance across the gateway opening, when the remainder of the movement will be automatically accomplished.

15 The tracks may be set at any desired "pitch" or inclination, but generally 1 in 20 will be employed, or the pitch may be different at each side of the peak of the track, for instance 1 in 20 at one side, and 1 in 25 20 or 30 at the other side, but these proportions may be varied as required. If, after the gate is set up, it is found to run too fast or too slow, the pitch of the tracks may be altered to any extent by releasing the supports for the tracks and setting them at a higher or lower point upon the head members 12 and 14, as will be obvious.

25 The post 11 is provided with a vertical slot 29 and extending through this slot at 30 its upper end is a supporting beam 30 having downwardly directed brackets 31-32 at its ends. The beam member 30 is supported at suitable intervals by standards 33-34. A vertical guide member 35 is 35 spaced from the post 11 at the opposite side of the gate, and is provided with a slot indicated at 44 similar to the slot 29 of the post 11. Pivoted at 36 in the bracket 31 is a lever 37, while a similar lever 38 is pivoted 40 at 39 in the bracket 32. The lever 38 extends at one end through the slot of the post 11 and terminates above the gate, while the confronting end of the lever 37 extends through the slot of the post 35 and terminates in relatively close proximity to the confronting end of the lever 38. The levers 37-38 are coupled at 40 to the gate by chains or similar flexible devices 41, the connecting device 40 being preferably 45 located about centrally of the gate and extending through the central vertical member 20, as shown in Fig. 2. The flexible member 41 is thus connected to the vertical and

longitudinal center of the gate. Guides 45-46 are located adjacent to the posts 11 and 55 35 to prevent undue lateral movement of the lower portion of the gate.

The levers 37-38 may be of any required length, and are provided at their outer ends with pull members 42-43. The levers 37-60 38 will be of sufficient length so that the pull members 42-43 are in convenient position for a person in a vehicle or on horseback approaching from either side. By this simple arrangement it will be obvious 65 that as a person approaches a gate he pulls downwardly upon the member 42 or 43, as the case may be, with the result of causing the chains 41 to pull the gate toward the levers 37-38, and at the same time exerting 70 an upward pulling force on the gate and causing the travelers to move upwardly upon the adjacent inclined portions of the tracks 16-17 until the gate reaches their central positions when the travelers will 75 move down the other inclined portions of the tracks and complete the movement automatically by gravity as before described. After the occupant of the vehicle passes through the gateway opening he pulls downwardly upon the other member 42 or 43 as the case may be, with the result of causing the gate to close by the same movements, in reverse order, as before described.

The improved device is simple in construction, can be inexpensively manufactured and of any required size and any suitable material.

Having thus described the invention, what is claimed is:

In a gate apparatus; a supporting frame including head members, coacting tracks carried by said members, each of said tracks including oppositely inclined portions adjustable independently of each other vertically of the adjacent head member, a gate having travelers respectively engaging said tracks, and means for operating the gate to slide upon said tracks.

In testimony whereof I affix my signature 100 in presence of two witnesses.

HENRY L. COATS.
